UNITED STATES PATENT OFFICE.

EBENEZER A. W. JEFFERIES, OF DETROIT, MICHIGAN, ASSIGNOR TO THE AMERICAN CONSTRUCTION COMPANY, OF SAME PLACE.

RAILROAD-TIE.

SPECIFICATION forming part of Letters Patent No. 657,492, dated September 4, 1900.

Application filed May 24, 1900. Serial No. 17,902. (No model.)

To all whom it may concern:

Be it known that I, EBENEZER A. W. JEFFERIES, a citizen of the United States, residing at the city of Detroit, in the county of Wayne and State of Michigan, have invented certain new and useful Improvements in Railroad-Ties, of which the following is a specification.

My invention has relation to a railroad-tie, the body or main portion whereof is formed of concrete or artificial stone, and in such connection it relates to the construction and arrangement of such a tie.

The principal objects of my invention are, first, to provide an elastic railroad-tie the body of which is formed of concrete or similar material reinforced near its upper face by metallic rods or bars and near its base by metallic strips, so that the body shall possess the necessary resilience or elasticity to successfully overcome the strain caused by the train passing over the ends of the tie; second, to provide in such a railroad-tie a simple and secure means for firmly holding two wooden blocks supporting the rails upon the concrete body of the tie, said means consisting, preferably, of the metallic rods or bars reinforcing the upper face of the body of the tie, and, third, to provide in such a railroad-tie a simple and secure means for firmly holding down the blocks of wood in the ends of the tie, said means permitting of the easy removal and replacement of the wooden blocks.

My invention, stated in general terms, consists of an elastic railroad-tie constructed and arranged in substantially the manner herein-after described and claimed.

The nature and scope of my invention will be more fully understood from the following description, taken in connection with the accompanying drawings, forming part hereof, in which—

Figure 1 is a front elevational view, partly in longitudinal section, of a railroad-tie embodying main features of my invention. Fig. 2 is a top or plan view of the tie, partly in horizontal section. Fig. 3 is an end elevational view of the tie; and Figs. 4 and 5 are cross-sectional views taken, respectively, on the lines *x* *x* and *y* *y* of Fig. 1.

Referring to the drawings, *a* represents the

body of the tie, consisting of concrete, artificial stone, or similar material. In the base of the body *a* is embedded a strip or strips *b* of wide metallic ribbon formed, preferably, of what is known as "expanded metal." Through the upper edge of the body *a* metallic rods or bars *d*, preferably two in number, are passed. At either end of the body *a* of the tie and in its upper surface is formed a recess *a'* for the reception of a block *e* of wood, upon which block the rail *f* may be spiked in the usual manner. The block *e* is shaped to fit into the recess *a'*, and has an inner curved or angular corner *e'*, which fits snugly into a corresponding depression of the recess *a'* when the block *e* is securely clamped in said recess. To clamp these blocks *e* into their respective recesses, the rods or bars *d* are passed through the blocks *e* and provided with washers *d'*, adapted to fit down upon the outer end of said blocks and to clamp the blocks to the body *a* when suitable nuts *d''* are advanced upon the ends of the rods or bars *d*. The base of each block *e* is provided with a dovetailed extension *e''*, adapted to slide in a complementally-formed groove *a''*, formed in the base of the recessed portion *a'* of the body *a*. This means of connection of the block *e* with the body *a* permits of the ready withdrawal and replacement of the blocks *e* when the nuts *d''* and washers *d'* are removed from the bars or rods *d*, and also, in connection with the angular or curved corner *e'*, fitting a corresponding depression of the recess *a'* of the body *a*, forms a firm or locking engagement for the block in the top of the body *a*. By reinforcing the top of the body *a* with the rods or bars *d* and embedding in the base of the body *a* a strip or strips *b* of metal whose surface is perforated—as, for example, in what is known as "expanded metal"—the body *a* is rendered sufficiently resilient or elastic to stand the strain upon the tie caused by the passage of a train over the rails *f* thereof.

It will be manifestly obvious that modifications may be made in the shape or form of the strip or strips of metal to be embedded in the concrete or other similar body of the tie to form an elastic strengthening-ligature without departing from the spirit and scope

of my invention, and hence I do not wish to be understood as limiting myself to the precise construction and arrangement of the said strip or strips as illustrated in the drawings; 5 but

Having thus described the nature and objects of my invention, what I claim as new, and desire to secure by Letters Patent, is—

1. A railroad-tie, comprising a body of concrete or similar material, a strip or strips of metal embedded therein, blocks arranged at both ends of said body at or near the upper face thereof, and a reinforcing bar or bars traversing said body and block, substantially 15 as and for the purposes described.

2. A railroad-tie, comprising a body of concrete or similar material, a strip of metal embedded in the base of said body, a wooden block arranged at either end of said body at 20 or near its upper face, and reinforcing bars or rods traversing the body and the blocks, said bars or rods adapted to clamp said blocks

to the body of the tie, substantially as and for the purposes described.

3. A railroad-tie, comprising a body of concrete or similar material having either end recessed, in combination with a wooden block adapted to fit into the recess at either end of the concrete body, a dovetailed projection formed on the base of said wooden block and 30 adapted to slide in a complementary groove formed in the base of said recess, and reinforcing bars or rods adapted to traverse the body and the blocks and to clamp said blocks to said body, substantially as and for the purposes described. 35

In testimony whereof I have hereunto set my signature in the presence of two subscribing witnesses.

EBENEZER A. W. JEFFERIES.
